UNITED STATES PATENT OFFICE.

CORNELIUS KIMPLEN, OF MINNEAPOLIS, MINNESOTA, ASSIGNEE TO CARRIE A. SHOVE,
OF MINNEAPOLIS, MINNESOTA.

ROCK-BREAKING MACHINE.

1,067,229.

Specification of Letters Patent.

Patented July 8, 1913.

Application filed December 12, 1910. Serial No. 596,813.

To all whom it may concern:

Be it known that I, CORNELIUS KIMPLEN, a citizen of the United States, residing at Minneapolis, in the county of Hennepin and State of Minnesota, have invented a new and useful Improvement in Rock-Breaking Machines, of which the following is a specification.

My invention relates to improvements in rock crushers and has as its principal object the simplification of operating and adjusting mechanism together with the strengthening of the main structure.

The form of crushing jaws is improved and the entire device rendered more efficient and safe by a structure which will be explained in detail.

In the drawings with which I have illustrated my device and which form part of my specification, Figure 1 is an end elevation of my device; Fig. 2 is a section on the line X—X, Fig. 1; Fig. 3 is a section on the line Y—Y, Fig. 2; Fig. 4 is a partial plan showing a single crushing unit; Fig. 5 is a side view partly in section of the connection of the lever and main shaft, and Fig. 6 is a section on the line Z—Z, Fig. 5.

In the drawings I show a supporting structure made up of a base portion A, supporting pillars B, a head frame C and a hopper D. In the base is journaled the main shaft 2 operating the levers 3 of the operating mechanism carried by the head frame. The base A may be supported on any suitable foundation such as the timber frame E illustrated. The base A is a rectangular metal shell having top and bottom flanges 4 and 5 and walls 6 carrying the shaft 2 journaled in boxes 7. Ribs 8 are formed in the base to support the flanges 4 and 5 under the pillars and bearings. The bearing points of the shaft are formed with annular channels 9 separating cylindrical bearings 10, 11 and 12, the diameters of the successive bearings decreasing toward the exterior of the frame. The box 7 fits the shafting and has holes 13 for lubrication opening into an oil cup 14 in the frame. A pulley 15 is fixed to the shaft 2 at one end and is supplied with a drive belt 16 from any suitable source of power. A small drive pulley 17 is fixed to the shaft near the large pulley.

The pillars B are formed with cylindrical shafts 20 and top and bottom flanges 21 and

22 adapted to be bolted to the adjacent structure by bolts 23. The pillars B rest upon the top flange 4 of the base A above the walls thereof. The head frame C is a substantially rectangular metal shell having side walls 25 and a bottom flange 26 resting on the top flanges 21 of the pillars B. Ribs 27 carry the load from the wall to the pillars. The upper part of the frame is arch shaped, open at the top and formed with an upwardly extending neck having side walls 28 and end walls 29, which support the crushing jaws and their operating parts hereinafter described. The neck walls 28 and 29 carry a flange 30 extending within and without the walls, stiffening the latter and forming a support for the hopper D. The hopper D is an outwardly expanding rectangular rim resting on the flange 30 of the head frame and fixed thereto by set bolts 31, and fitted to hold a supply of rock above the jaws of the crusher.

I have shown a crusher having three crushing units which are similar in form and operation. The number of crushing units in no way effects my invention, and may be increased or decreased as desired, in making the machine. In the crusher which I have illustrated, the opening in the top of the head frame is divided by two bridges 32 into three oblong openings 33, 34 and 35, substantially rectangular in form, lying transversely of the crusher. Against the end walls of said openings are fixed the stationary jaws 36 of the crusher. These jaws are fixed to the side walls 28 of the neck of the crusher by bolts 37 which pass through the walls into recesses 38 formed therein. The stationary jaws have their bearing against the walls 28 and each is formed with a median lug 39 on its bearing face 40 lying in the recess 38 of the wall. The lug has two forwardly converging plain surfaces 41 and 42 against which rest the beveled faces of the nuts 43 on the bolts 37. The pressure of the nuts against the convergent faces of the lug 39 holds the jaw 36 against the wall 28, and by increasing the pressure on one of the nuts and decreasing the pressure on the other, the jaw may be adjusted vertically on the neck wall. The lug is slotted vertically at 45 to receive the body of the bolt and allow the vertical movement of the jaw in adjusting it. The crushing face of the jaw is inclined toward the center line of the

crusher at an oblique angle which becomes more oblique in the lower part of the face and curves inward sharply at the lower extremity of the face. At the sides of the fixed jaws 36 are cheek pieces 46 fixed by stud bolts 47 to the bridges 32 and the neck walls to present removable surfaces protecting these parts during operation of the crusher. On the center line of the crusher, the bridges 32 and end walls 29 of the neck are formed with upstanding lugs 48 which constitute an open topped bearing 50 for the gudgeons 49 of the operating levers 3. Longitudinal movement of the gudgeons in their bearings 50 is prevented by the partition walls 51 rising above the lugs 48 at the ends of the gudgeons 49.

The operating levers 3 are massive metal bars of substantially rectangular cross section hanging vertical between the crusher jaws 36 and oscillating transversely of the crusher on the gudgeons 49 resting in the open bearings 50. The upper end on the lever is provided with a loop 52 by which the lever may be raised or lowered into position. The lower end of the lever is formed with a yoke 53 embracing an eccentric 54 on the operating shaft by which it is oscillated. The lever has economy slots 55 in its shaft to lighten the structure. At the upper end of the lever, below the gudgeons, the faces of the lever lying longitudinally of the crusher diverge downwardly and are formed with dove-tail grooves 56 which are narrower at the bottom than at the top and lie longitudinally of the lever and into which fit corresponding tenons 57 on the active crushing jaws 58. Each of the jaws 58 is formed to fill substantially the space between the cheeks 46 of the openings 33, 34, and 35 and has a crushing face 59 formed with an upper portion 60 at an oblique angle with the axis of the lever 3 and a lower portion 61 curving back toward the lever. Each of the jaws 58 forms, with the opposed stationary jaw 36, a V shaped opening into which stone of suitable dimensions may pass to be crushed. The curve 61 at the bottom of the movable jaw is shaped to form with the curve 62 of the stationary jaw 36, a passage gradually narrowing toward the bottom to allow the escape of material crushed to the desired dimensions. The curve of the movable jaw is continued above the curve of the lower jaw, and the upward adjustment of the stationary jaw narrows the aperture 63 at the lowest point of the jaws, and produces a finer crushed product. By lowering the fixed jaw 36 the aperture is widened and the size of the escaping fragments of material is increased.

The crushing faces of the opposed jaws are so designed that a gradually narrowing aperture is formed in which the material is crushed by the action of the movable jaw.

This action is produced by the oscillation of the lever 3 in the bearings and is limited by the cam 54 on the shaft 2. The cam 54 is proportioned to produce a lateral movement of substantially one-eighthieth of the length of the lever 3 thus causing a very slight angular movement of the lever and an extremely slight transverse movement of the active crusher jaws 58 which as described, lie near the fulcrum of the operating lever 3. The cam 54 is formed integral with the operating shaft 2 and has a cylindrical surface 65 with beveled ends 66 extending to concentric cylindrical surfaces 67 of less diameter on either side of the cam, forming a broadly banded surface to which is fitted a split box 68 the parts of which are bolted together with bolts 69 at the top and bottom and slide on Babbitt bearings 70 in the yoke 53 of the lever 3. The lower end of the yoke 53 is filled at the sides by blocks 71 having upper ends 72 hollowed out to permit a considerable upward movement of the lever 3 upon the cam 54 in addition to that caused by the rotation of the shaft 2. Below the block 71 is a strap 73 to which the block 71 is attached and which is itself attached to the ends of the yoke 53 by bolts 74. A slight motion of the lever yoke 53 longitudinally of the shaft is provided for by spaces 75 between the cam 54 and the inclosing sides 76 of the yoke 53. Between the operating levers 3 fly wheels 80 are fixed to the shaft 2 adjacent to the levers 3.

Directly below the apertures 63 of the crushing jaws are troughs 81 extending on each side of the levers to the end on the head frame C where they empty through the end wall into a spout 82 for the delivery of the crushed material. The material falling through the apertures 63 drops into the troughs 81 and is transferred to the end of the machine by screw conveyers 83, the shafts 84 of which pass through the wall of the head frame and are operated by gears 85 fixed thereon. The gears 85 of the two screws 83 are driven by a pinion 86 journaled on a stud shaft 87 fixed in the wall of the head frame C. The pinion 86 is driven by a pulley 88 and belt 89 from the pulley 117 on the operating shaft 2. By removing the longitudinal trough 81 and placing a transverse trough 90 under each pair of crushing jaws, different materials and sizes may be crushed simultaneously in the 120 crusher. The bearings 50 are protected by a hood 91 which extends longitudinally of the crusher resting on the bridges 32 and the end walls of the neck.

In operation material to be crushed is introduced into the hopper D in a sufficiently divided state to enter the top of the aperture between the crushing jaws. The operating shaft being rotated, the operating levers are oscillated by the cams on the shaft and the 130

active crushing jaws moved in opposition to the fixed jaws of the crusher. At each stroke of the active jaws 58 the material caught between them and the fixed jaws 36, 5 is either crushed or spawled to the slightly lessened diameter required to meet the movement of the jaws. Upon reversing the motion of the levers, the material so crushed or spawled is freed to fall to a point where 10 it again fills the space between the open jaws, at which point it is again subjected to the slight crushing movement of the active jaws on their next stroke. It will be readily understood that the operation is carried on by a succession of short crushing 15 movements produced by slight forces acting upon levers having relatively long power arms. The rapid succession of short strokes is more effective in crushing than longer 20 slower strokes, and is very much more economical of power. As the material passes from the crushing jaws it is caught in the conveyer troughs and carried by the action of the screw to the exterior of the crusher.

25 The introduction of any non-crushable material like pieces of iron, between the jaws of my crusher cannot injure the machine. Since the lever carrying the active jaws is free to rise a considerable distance from between the stationary jaws thus enlarging the 30 aperture between the jaws to allow the passage of the non-crushable material. Or if the material is too large to pass out, the lever will hang in its raised position until the 35 difficulty is noted and corrected.

In accordance with the patent statutes I have described the principles of operation of my invention together with the apparatus which I now consider to represent the best 40 embodiment thereof but I desire to have it

understood that the construction shown is only illustrative and that the invention can be carried out by other means and applied to uses other than those above set forth within the scope of the following claims. 45

Having described my invention, what I claim as new and desire to protect by Letters Patent is:—

1. In a crusher, a supporting frame, a pair of similar crushing faces mounted on 50 said frame in opposed position, an oscillating member freely journaled in an open bearing to oscillate between said faces and above them and adapted to have its weight and momentum directed downward on the 55 material on each of said faces alternately and means for oscillating said member.

2. In a crusher, a supporting frame having a vertical passage therethrough, a pair of crushing faces projecting inwardly from 60 the wall of said passage and mounted upon said frame, said faces being horizontally opposed to each other, an oscillating member suspended in an open journal bearing to oscillate between said faces and above them, 65 said oscillating member having crushing faces opposed to the crushing faces on the wall of said passage and adapted to have its weight and momentum directed downward on the material on each of said faces 70 in the wall of said passage alternately, and means for oscillating said member.

In testimony whereof, I have signed my name to this specification, in the presence of two subscribing witnesses.

CORNELIUS KIMPLEN.
